UNITED STATES PATENT OFFICE.

EDWARD J. DOBERSTEIN, OF CHICAGO, ILLINOIS, ASSIGNOR TO GOODMAN MANUFACTURING COMPANY, OF CHICAGO, ILLINOIS, A CORPORATION OF ILLINOIS.

SCRAPER LOADING APPARATUS.

Application filed December 29, 1922, Serial No. 609,570. Renewed September 7, 1926.

This invention relates to improvements in apparatus for handling loose material, and more particularly to draft operated scraper devices adapted to gather and transport loose material for loading into a car or the like. The apparatus herein shown and described is particularly adapted for use in mines, or under similar conditions where working space is limited, as for instance, in the room and pillar system of coal mining, in which coal is transported from the working face in a mine room by means of a draft operated scraper, to be loaded in mine cars mounted on tracks in an entry or gallery.

The principal object of the invention is to provide a novel construction of loading chute adapted to extend over a mine car, upon which chute the scraper may be moved into position over the car so as to be unloaded therein. A further object is to provide a novel arrangement of hoisting device or mechanism for actuating and controlling the draft ropes, mounted on the loading chute. A further object is to provide means for transporting the entire mechanism so as to be readily moved from place to place in the mine.

The invention may be best understood by reference to the accompanying drawings and the description relative thereto, disclosing one form of apparatus in which my invention is embodied.

In the drawings, Figure 1 is a side view of a loading chute, constructed in accordance with my invention, with a part thereof shown in section.

Figure 2 is a top view of the loading chute shown in Figure 1.

Figure 3 is a plan view of a loading chute, together with a draft operated scraper, as installed in a mine.

Figure 4 is a side view of the apparatus shown in Figure 3.

Figure 5 is a view similar to Figure 3, but illustrating the manner in which the chute may be withdrawn from loading position at the entrance of a mine room into position in the entry for transportation to another point in the mine.

Figure 6 is a side view of the apparatus shown in Figure 5, in which the loading chute is shown in raised position on a transporting device movably mounted on the track.

Figure 7 is a detailed view taken on line

7-7 of Figure 1, showing the draft operating mechanism at one end of the loading chute.

Figure 8 is a sectional view taken on line 8-8 of Figure 1.

Figure 9 is a sectional view taken on line 9-9 of Figure 1.

Figure 10 is a plan view illustrating one form of truck which may be used for transporting the loading chute from place to place.

Figure 11 is a sectional view of the truck taken on line 11-11 of Figure 10.

Figure 12 is a sectional view of the truck taken on line 12-12 of Figure 10.

In the embodiment illustrated, the loading chute comprises an inclined runway 10 adapted to have contact with the ground, an unloading platform 11 at the upper end of the inclined runway and supporting means, including an upright support 12 connected to the unloading platform 11, and a second upright support 13 connected to the inclined portion 10. Suitable guideways 14, 14 are provided along opposite sides of the inclined runway 10. In the form shown, these guideways are continued along opposite sides of the loading platform 11 but at relatively greater height than the portions 14, 14 of said guideways, as indicated at 15, 15.

The entire chute is preferably mounted for movement on the mine floor and to this end the supporting member 12 is provided with suitable wheels 16, 16 adapted to engage the ground, as shown in Figures 1 and 7. In the form shown these wheels are journaled in a frame member 17 (see Figure 7) which is connected to the supporting member 12 by means of an expandable joint, which in the present instance, comprises a jack member 18, having an upper portion thereof threaded in a stud 19 on the supporting member 12 and the lower portion thereof threaded in the frame member 17. The jack member 18 may be rotated in the usual manner to adjust the height of the frame member 12 with respect to the ground.

The supporting member 13 connected with the inclined portion 10 of the chute is provided at its lower end with supporting wheels 20, 20, mounted on a frame member 21. In this instance the frame member 21 is pivotally connected to the supporting member 13, so that the wheels may readily adjust themselves with the inequalities of

the floor. The supporting member 13 is also preferably provided with an extensible connection which, in this instance, comprises a rotatable jack member 22 having upper and lower threaded portions engaging respectively upper and lower portions, 23 and 24, of the member 13.

Power devices for controlling and actuating a draft operated scraper are mounted on the chute. These power devices are preferably arranged at the far end of the loading platform 11, opposite the inclined runway 10, and in the form shown are mounted on the supporting member 12. Any suitable power devices and operating mechanism may be provided for this purpose, it being understood that it is preferable to provide two winding drums, one for the head rope of the scraper, to provide a forward draft therefor and another for the tail rope to provide a rearward draft therefor. In the form shown this mechanism includes a winding drum 30 loosely mounted on a shaft 31, and another drum 32 loosely mounted on a parallel shaft 33. These drums are driven by a motor 34 through suitable gearing, such as an armature pinion 35 and gear 36 on the stub shaft 37. A second gear 38 rotates with the gear 36 and is meshed with the gear 39 keyed to the shaft 33 on which the drum 32 is mounted as aforesaid. Said drum may be operatively connected to the shaft 33 through a sliding clutch 40 or its equivalent. In the present instance the clutch shown is of the cone type. The gear 39 on the shaft 33 is meshed with the gear 41 on the shaft 31 and this shaft in turn may be operatively connected to the second drum 30 by means of a second clutch 42. It will be observed that the drums 30 and 32 will be rotated in opposite directions owing to the meshed relationship of the driving gears 39 and 41 which drive the respective drums. The motor, drums and gearing are arranged on axes of revolution which are substantially in vertical alignment with each other so as to provide a particularly compact operating mechanism.

The use of the chute will be best understood by referring to the Figures 3, 4, 5 and 6. In Figures 3 and 4 the scraper is indicated at 50 and is provided with a head rope 51 and a tail rope 52. This scraper is adapted to be reciprocably moved by the head and tail ropes which may be trained about suitable guide sheaves and anchored in the mine room in any suitable manner. The head rope 51 passes over a roller 32^a and is wound on the lower drum 32, while the tail rope passes over a roller 30^a and is wound over the upper drum 30. It will be understood that the tail rope passes from its drum into the room and about suitable sheaves, so as to provide a rearward draft on the scraper to pull it backwardly into position to gather a load,

whereas the head rope 51 is attached to the front end of the scraper and is arranged to exert a forward draft thereon. The guiding means which control the movement of the scraper are not shown, as they form no part of the invention, and may be arranged in any suitable manner so as to direct the forward movement thereof into the loading runway. This chute is arranged so as to extend over the mine cars or the like with the loading platform 11 directly over the tracks in position to permit the scraper to be emptied into the car thereunder when said scraper is on the loading platform.

In the form shown the scraper 50 is of the bottomless type as indicated in Figure 3 and a suitable opening 11^a is formed in the loading platform 11 so as to permit the material to be dropped through said platform into the car when the scraper is in position over said opening. As for the broader features of my invention, however, it will be understood that other forms of scrapers may be used, and various arrangements of dumping means may be provided, as desired.

The chute may be rigidly held in any desired position over the car by suitable means such as jacks 54, 54 engaging the upright member 12 and jacks 55, 55 engaging the sides 14 of the inclined portion 10. A suitable cross member or stop 56 is provided intermediate the chute opening 11^a and the hoisting drums, so as to limit the movement of the scraper together with the loose material therein.

It will be observed in Figures 3 and 4 that the inclined portion of the chute extends into the neck of a mine room. It will be understood, that the entries in which the tracks are laid are usually as narrow as is consistent with mining conditions, so that the space for moving and transporting apparatus of the class described is generally quite limited.

Means for transporting the loading chute from place to place, as for instance, from one room neck to another, may comprise any suitable supporting device mounted on the track rails and adapted to be moved into supporting position underneath the loading platform 11. In the form illustrated in Figures 5 and 6, and 10 to 12, inclusive, I have shown a truck indicated at 60 which is particularly adapted for this purpose. The truck comprises a frame 61 of any suitable construction provided with flanged wheels 62, 62 adapted to engage the track. The truck is provided with an extensible supporting device which is low enough to run under the chute when it is supported on the ground in the loading position and thereafter the extensible supporting device may be elevated into position to engage and raise the entire chute from the ground, as shown in Figure 6. In the present instance the extensible device comprises

a lifting jack 63 embodying any standard construction and having its base mounted on cross member 64 on the truck. The upper end of the lifting jack is provided with a supporting frame member 66 upon which is mounted a turntable 67 which is pivotally connected for movement in a horizontal plane on the supporting frame member 66 as shown in Figure 11. In the form shown the turntable 67 is provided with a plurality of bearing members 68, 68, which engage the supporting frame 66. Suitable guide means are provided for the supporting frame 66, as for instance a plurality of vertically disposed guide pins 69, 69 extending downwardly through guide members 70, 70 mounted on the truck frame member 61. When in use, the truck is moved into position underneath the chute and the jack 63 is then actuated to lift the entire chute out of engagement with the ground, in which position it is then supported on the turntable, as indicated in full lines in Figure 5. The truck, together with the chute, may then be moved along the track into a second position, as indicated in dotted lines in Figure 5, and the entire chute may then be swung about on the turntable 67 into substantially longitudinal alignment with the track, as is also indicated at Figure 5, in which latter position the chute may be readily transported along the track by moving the truck therealong in any desired manner. The chute may then be positioned in a new room neck by reversing the sequence of movements described above and illustrated in Figure 5.

It will be noted that the chute is arranged and constructed so that the inclined runway and thereof will be substantially counterbalanced by the operating mechanism carried on the supporting member 12 which is on the opposite side of the track and therefore on the opposite side of the point of pivotal movement of the chute when it is pivotally swung on the supporting truck 60.

My invention is not limited to the particular form of truck shown for transporting the loading chute, it being understood that similar elevating and turntable devices may be mounted either on a mine car or on a relatively small mining locomotive, as for instance, a locomotive of the gathering type, upon which such elevating and turntable devices could be readily installed, if desired. With reference to the loading chute itself, it will also be understood that while I have shown a specified form in which my invention may be embodied, other forms and constructions may suggest themselves to those skilled in the art for accomplishing substantially similar results, without departing from the spirit and scope of my invention. I do not therefore wish to be understood as limiting myself to the specific details of mech-

anism illustrated or described herein, excepting as specifically limited in the appended claims.

I claim as my invention:

1. In a scraper loading apparatus, in combination, a movable frame adapted to span a track and provided with a passageway therethrough for cars, an inclined runway extending laterally from above said passageway to engage the ground, a draft operated scraper device arranged for movement along said runway, means permitting discharge of said scraper in position over said passageway, means for temporarily fixing said frame against lateral movement, and supplementary means movable on said track, adapted to support said frame bodily for transportation when said temporary fixing means are inoperable.

2. In a scraper loading apparatus, in combination, a movable frame adapted to span a track and provided with a passageway therethrough for cars, an inclined runway extending laterally from above said passageway to engage the ground, a draft operated scraper device arranged for movement along said runway, means permitting discharge of said scraper in position over said passageway, means for temporarily fixing said frame against lateral movement, and supplementary means movable on said track, adapted to support said frame bodily and permitting pivotal movement thereof into alignment with said track, for transportation when said temporary fixing means are inoperable.

3. In a scraper loading apparatus, in combination, a movable frame adapted to span a track and provided with a passageway therethrough for cars, an inclined runway extending laterally from above said passageway to engage the ground, a draft operated scraper device arranged for movement along said runway, means permitting discharge of said scraper in position over said passageway, means for temporarily fixing said frame against lateral movement, and supplementary supporting means movable on said track provided with an elevating device adapted to engage and support said frame bodily for transportation when said temporary fixing means are inoperable.

4. In a scraper loading apparatus, a movable frame adapted to span a track and provided with a passageway therethrough for cars, an inclined runway extending laterally from above said passageway to engage the ground at one side of the track, a draft operating device mounted on said frame at the opposite side of said passageway, a scraper operatively connected with said draft operating device for movement along said runway, means permitting discharge of said scraper in position over said passageway, and means for temporarily fixing said frame against lateral movement, and supplement-

- temporary means movable on said track adapted to support said frame bodily for transportation when said temporary fixing means are inoperable.
5. In a scraper loading apparatus, a movable frame adapted to span a track and provided with a passageway therethrough for cars, an inclined runway extending laterally from above said passageway to engage the ground at one side of the track, a draft operating device mounted on said frame at the opposite side of said passageway, a scraper operatively connected with said draft operating device for movement along said runway, means permitting discharge of said scraper in position over said passageway, and means for temporarily fixing said frame against lateral movement, and supplementary means movable on said track adapted to
- 10 support said frame bodily and permitting pivotal movement thereof into alignment with said track, for transportation when said temporary fixing means are inoperable.
6. In a scraper loading apparatus, a movable frame adapted to span a track and provided with a passageway therethrough for cars, an inclined runway extending laterally from above said passageway to engage the ground at one side of the track, a draft operating device mounted on said frame at the opposite side of said passageway, a scraper operatively connected with said draft operating device for movement along said runway, means permitting discharge of said scraper in position over said passageway, 35 means for temporarily fixing said frame against lateral movement and supporting means movable on said track provided with an elevating device adapted to engage and support said frame bodily for transportation 40 when said temporary fixing means are inoperable.

Signed at Chicago, in the county of Cook and State of Illinois, this 27th day of December, 1922.

EDWARD J. DOBERSTEIN.
